UNITED STATES PATENT OFFICE.

HOWARD H. WALKER, OF CAMBRIDGE, MASSACHUSETTS.

DESIGN FOR A FINGER-RING OR SIMILAR ARTICLE.

51,665.

Specification for Design.

Patented Jan. 1, 1918.

Application filed September 1, 1917. Serial No. 189,417. Term of patent 3½ years.

To all whom it may concern:

Be it known that I, HOWARD HENRY WALKER, a citizen of the United States, residing at Cambridge, in the county of Middlesex and State of Massachusetts, have invented a new, original, and ornamental Design for Finger-Rings or Similar Articles, of which the following is a specification, reference being had to the accompanying drawing, forming part thereof.

The figure is a perspective view of a finger-ring illustrating my new design.

I claim:

The ornamental design for a finger ring or similar article, as shown.

Signed at Boston, in the county of Suffolk and State of Massachusetts, this 29th day of August, 1917.

HOWARD H. WALKER.
